(57) **CLAIM**

The ornamental design for a container-lid assembly, as shown and described.

DESCRIPTION

FIG. 1 is a front elevational view of a container-lid assembly embodying our new design;

FIG. 2 is a side elevational view of the container-lid assembly taken according to arrow II of FIG. 1;

FIG. 3 is top plan view of the container-lid assembly of FIG. 1; and,

FIG. 4 is a bottom view of the container-lid assembly of FIG. 1.
